(57) **CLAIM**

The ornamental design for a coldness/heat preserving container, as shown and described.

DESCRIPTION

FIG. 1 is a front elevational view of the coldness/heat preserving container showing my design, the rear view being identical thereto;

FIG. 2 is a top plan view thereof, the bottom plan view being identical thereto;

FIG. 3 is a right side view thereof;

FIG. 4 is a left side view thereof;

FIG. 5 is a cross-section taken across line A-A of FIG. 2; and,

FIG. 6 is a cross-section taken on line B-C-D-E of FIG. 2.
